No. 25,680.

PATENTED OCT. 4, 1859.

T. P. SINK.
OYSTER DREDGER.

UNITED STATES PATENT OFFICE.

THOMAS P. SINK, OF FAIRTON, NEW JERSEY.

IMPROVEMENT IN OYSTER-DREDGES.

Specification forming part of Letters Patent No. 25,680, dated October 4, 1859.

To all whom it may concern:

Be it known that I, THOMAS P. SINK, of Fairton, in the county of Cumberland and State of New Jersey, have invented a new and useful Oyster-Dredging Machine; and I do hereby declare that the following is a full, clear, and exact description of the construction and operation of the same, reference being had to the accompanying drawing, making a part of this specification.

The usual method of dredging for oysters is to affix to the gunwale of the vessel a piece such as is represented by X in the annexed drawing, with an upright attachment, such as Y, at one end thereof, for the purpose of sustaining or holding the rope to which the dredge is attached while the boat is in motion, and also while the dredge is being hauled upon the deck of the boat. Sometimes an arrangement of the wheel and axle or of the windlass is employed for the purpose of hauling in the dredge.

In my new device I construct an upright block or chuck, A, which is set vertically by means of a pin projecting from its under side into a corresponding aperture in a rest or bed-plate, but leaving space sufficient to allow the block or chuck to rotate horizontally either wholly or partly around its axis. In this block or chuck a pulley, B, is constructed, turning upon a pin passing horizontally through its center.

C and C' are vertical friction-rollers affixed to the edges of that face of the chuck or block which is nearest to the stern of the boat. Alongside of the other face of the block or chuck, which should be convex in form, and thence extending toward the forward part of the boat, I place a horizontal roller, E, supported by proper bearings constructed in two uprights, D and D'. The diameter of this roller should be about three inches, and its length from three to five feet, according to the size of the boat, its height and that of the uprights corresponding with the elevation of the chuck or block. The useful effect of the roller will be increased by fluting it, which will check the tendency of the dredge to slide back into the water.

At one extremity of the roller, as at F, I place a ratchet-wheel, so as to prevent the roller from turning in any other direction except inward toward the deck.

The face of the upright D which adjoins the chuck or block should be concave, so as to correspond with the convex side of the chuck or block, and the concave and convex surfaces should be set as near together as will admit of the easy play of the one into the other.

In the use of this device the rope to which the dredge is attached is placed over the pulley, and the block or chuck, by its capacity to rotate, readily adapts itself to any change in the direction which the rope may take in consequence of a change in the course of the boat as the dredge is dragged along after it. In drawing in the dredge with its contents the rope passes across one or both of the friction-rollers and over the pulley, and the pin of the pulley gradually assumes a direction coinciding with that of the roller, in which position it will generally be found when the upper extremity of the dredge has been drawn up to or upon the pulley or the block. By a slight forward motion of the rope the upper extremity of the dredge is then caused to slide onward upon the roller, which, by means of the ratchet-wheel, can turn only in a direction inward toward the deck, and the dredge is finally raised up on the roller and its contents discharged.

The weight of a full dredge is generally about four hundred pounds, and it is evident that an arrangement of friction-wheels, a rotating pulley-block, such a roller such as above described will greatly relieve the labor of those who are required to handle this weight. Indeed, I have found that by means of my device one man may perform the same work which, without it, would have required the efforts of three men.

Having thus fully described my invention, what I claim therein as new, and desire to secure by Letters Patent, is—

The arrangement and combination of the chuck or block A and its pulley B with the roller E, the respective parts being formed and operating substantially in the manner and for the purposes above set forth.

T. P. SINK.
